UNITED STATES PATENT OFFICE

169,130

EYESHADE

Benona W. Dieroff, Fair Oaks, Calif.

Application December 1, 1952, Serial No. 22,507

Term of patent 14 years

(Cl. D54—1)

To all whom it may concern:

Be it known that I, Benona W. Dieroff, a citizen of the United States, residing at Fair Oaks, county of Sacramento, and State of California, have invented a new, original, and ornamental Design for an Eyeshade, of which the following is a specification, reference being had to the accompanying drawing, forming a part hereof.

Fig. 1 is a perspective view of an eyeshade showing my new design;

Fig. 2 is a plan view thereof; and

Fig. 3 is a side elevational view thereof.

I claim:

The ornamental design for an eyeshade, as shown.

BENONA W. DIEROFF.
